ATTORNEY.

UNITED STATES PATENT OFFICE.

FRANK WOLF, OF NEW YORK, N. Y.

ARCH SUPPORT.

Application filed July 7, 1923. Serial No. 649,996.

This invention relates to arch supports designed to be inserted in the shoe of the user, and has for its main object to provide a support which is simple in construction, effective in operation, and comfortable and durable in use.

A further object of the invention is to provide an arch support of the character described, adapted to have a limited yielding movement in the direction of its length, and rigid on a line extending transversely of its central portion.

The invention has for its object also to provide an arch support flexible longitudinally, and rigid transversely of its central portion, with a cushion pad of yielding material.

With the foregoing and other objects in view, hereinafter stated, the invention consists of the novel construction, combination, and arrangement of parts hereinafter more specifically stated, and illustrated in the accompanying drawings, wherein is shown a device and modifications thereof embodying the structure of the invention in its preferred form, but it is to be understood that changes, variations, and modifications may be resorted to without departing from the scope of the invention.

In describing the invention in detail, reference is had to the accompanying drawings which form a part of this specification, and wherein like characters of reference indicate corresponding parts throughout the several views, and wherein:

Fig. 1 is a plan of the underside of an arch support embodying the invention;

Fig. 2 is a plan of a supporting plate provided with means for retaining a cushion pad;

Fig. 3 is a front perspective of the tread of a cushion pad for the bearing plate;

Fig. 4 is a front perspective of the upper side of the cushion pad shown in Fig. 3;

Fig. 5 is a plan of pneumatic cushion pad substantially similar in outline to that shown in Figs. 3 and 4;

Fig. 6 is a central section taken on the line 6-6 of Fig. 5.

As illustrated in the drawings, the arch support is provided with a holding or supporting member 1, the main portion of which may be of any suitable outline adapted to be readily placed and maintained within a shoe.

A supporting plate 2 is secured to the underside of the member 1 by means of rivets 3, passing through said plate and member, and is provided with extensions 4 having their free ends bearing against the underside of the member 1.

The supporting plate is made of flexible material, preferably metal, and is bendable within limits longitudinally of its length in order to aid in producing a yielding movement responsive to the pressure on the foot of the user.

The supporting plate is also provided with a flange 5 curved upwardly from the plane of the supporting plate laterally thereof, so as to bear against the side of the arch of the foot of the user, and provide a support therefor. The flange is so shaped as to make the portion adjacent thereto and transversely thereof rigid so that while the supporting plate has a flexible or movable action in the direction of its length, produced largely by the extensions 4, the central transverse portion of the plate is inflexible, and bears uniformly against the side of the foot of the user. This rigidity is such that it causes the central part of the plate to press against and upwardly towards the arch, and such that the vertical part of the rigid plate presses inwardly towards the arch. In other words, the plate supports the arch upwardly and inwardly. This is maintained during the pressure of the foot on the plate, which pressure causes the plate to give longitudinally, but does not break down the plate because of its rigidity; and hence, even with a depressed longitudinal plate, the transverse rigidity holds the arch upwardly and inwardly. This cooperation gives a yieldable support and still prevents the arch from breaking down.

The undersurface of the supporting plate, as shown in Fig. 1, is also provided with a retaining flange 6, corresponding in contour with the outer margin of a cushion pad 7, and offset from the plane of the supporting plate 2 so as to form a curved recess within which the outer margin of the cushion is retained. The retaining flange 6 may be secured to the plate in any suitable manner, such as by welding. The flange 6 is substantially semi-circular and disposed at the middle portion of the plate and is open at one side to receive the rubber cushion block or pad 7. The flange 6, therefore,

holds the plate from flexing on a longitudinal axis, but as the plate extends at opposite ends beyond the flange 6, the ends of the plate are permitted to flex on a transverse axis.

The cushion 7, in most instances, is made flexible, preferably by constructing it of rubber, in the form of sponge rubber or otherwise, although in some instances it may be formed of leather or other suitable material. When formed of rubber, the cushion will have a limited yielding capacity by virtue of its own resilience, but when made of leather, or even in some instances when made of rubber, the cushion can be provided with cut-away portions 8, preferably angular in cross-section to provide means for increasing the yielding capacity of the cushion pad.

20. One or both of the opposite surfaces of the cushion may be provided with such cut-away portions, and such portions may be arranged transversely of the cushion, as shown in Fig. 3, or extend longitudinally thereof, as indicated at 9 in Fig. 4. Such cut-away portions serve to augment the yieldability of the rubber.

When a cushion pad is desired having an efficient yielding capacity, for use in shoes worn by persons requiring as much foot-ease as possible, a cushion 10 may be made of rubber and provided with a hollow interior 11, as indicated in Fig. 6, and also with a marginal edge similar to the cushion 7, adapted to be retained within the recess formed by the retaining flange 6. This pneumatic form may be used instead of the other forms described.

40. I have also provided a combined arch support and heel rest. In Fig. 1, the member 1 has an extension 20, provided with a tapering portion 21, which is provided with cup-shaped portions 22 of rubber, or the like, and those give an efficient rest for the heel portion of the foot.

Any form of heel, such as are well known on the market, may be used, but the com-

bination of a heel with an arch support is believed to be novel.

What I claim as new and desire to secure 50 by Letters Patent is:

1. An arch support comprising a support plate provided with yielding ends, a rigid flange projecting downwardly from the central portion of said plate and curved substantially semi-circular, said flange maintaining the plate from flexing about a longitudinal axis and permitting the ends of the plate to flex on a transverse axis, and a pad having edges fitted into said flange and lying against the under side and central portion of said plate.

2. An arch support comprising a support plate provided with a relatively wide central portion and narrow end portions at opposite ends of the central portion, a substantially semi-circular flange carried upon the lower side of the plate and projecting downwardly in overhanging relation relatively to the plate, and a pad having an edge portion fitting into said flange to hold the pad against the under side of the plate, said flange holding the central portion of the plate against flexing on a longitudinal axis and permitting the free flexing of said end portions of the plate.

3. An arch support comprising a support plate provided with yielding ends, retaining means carried upon the central portion of the plate at its under side and comprising gripping means disposed substantially semi-circularly on the plate, and a pad fitting against the under side of the plate and having an edge portion adapted to fit into said retaining means for clamping the pad against the plate to support the latter and reinforce the plate against flexing on a longitudinal axis but permitting the free flexing of the ends of the plate.

In testimony that I claim the foregoing 90 as my invention, I have signed my name hereunder.

FRANK WOLF.
